UNITED STATES PATENT OFFICE

BENEDICT F. PETERSON, OF MILWAUKEE, WISCONSIN

DESIGN FOR A CONFECTION

Application filed May 17, 1930. Serial No. 35,678. Term of patent 14 years.

To all whom it may concern:

Be it known that I, BENEDICT F. PETERSON, a citizen of the United States, resident of Milwaukee, in the county of Milwaukee and State of Wisconsin, have invented a new, original, and ornamental Design for Confections, of which the following is a specification, reference being had to the accompanying drawing, forming part thereof.

The figure is a perspective view of a confection showing my new design.

I claim:

The ornamental design for a confection, substantially as shown.

In testimony that I claim the foregoing I have hereunto set my hand at Milwaukee, in the county of Milwaukee and State of Wisconsin.

BENEDICT F. PETERSON.
